UNITED STATES PATENT OFFICE

DANIEL I. KEOUGH, OF LEWIS RUN, PENNSYLVANIA.

SAWMILL.

No. 881,004.

Specification of Letters Patent.

Patented March 3, 1908.

Application filed March 6, 1907. Serial No. 360,861.

To all whom it may concern:

Be it known that I, DANIEL I. KEOUGH, a citizen of the United States, residing at Lewis Run, in the county of McKean and 5 State of Pennsylvania, have invented certain new and useful Improvements in Sawmills, of which the following is a specification, reference being had therein to the accompanying drawing.

10 My invention relates to improvements in saw mills, and pertains more particularly to what are known as drag saws.

15 The object of my invention is to provide a saw mill of this character, in which all parts are permanently mounted in a portable frame, and at the same time producing a durable, simple and effective mill of the character described.

20 In the accompanying drawings, Figure 1, is a perspective view of my improved saw mill. Fig. 2, is a side elevation looking from the opposite side from that shown in Fig. 1. Fig. 3, is a top plan view. Fig. 4, is a perspective view of a section of the saw carrying 25 member and the saw attaching means.

Referring now to the drawings, 1 represents an elongated rectangular frame which is composed of heavy timbers to support the entire working part of the mill, so as to make 30 the mill easily transportable so as not to disturb any of the working parts of the mill. This frame 1 may be constructed of any desired manner, but the timbers are preferably mortised together to form a more solid 35 frame. The said frame is composed of the two bottom horizontal beams 2 and 3, and the upper horizontal beams 4 and 5 connected by the vertical standards 6, and the transverse beam 7. Connecting the stand- 40 ard 6 directly above the beam 2 is a second horizontal beam 8 which forms a guide for the saw carriage, as will be hereinafter more fully described. Between the beams 5 and 8 intermediate their ends, is a brace 9.

45 Within the frame and connected to the trans- 50 verse beams 7, are the vertical standards 9 and 10 which are connected at their lower ends with a beam 11 in a plane with the beam 2, and with a second beam 12, in a line with the beam 8, forming, as before stated, the guide-way for the saw carrying member. The upper transverse beam 7 is connected by a horizontal beam 13 while the beams 3 and 4 are braced by the beam 14. The 55 beams 3 and 4 adjacent the rear end is pro-

vided with a standard 15. The said standards 15 intermediate their ends are provided with journals 16 in which is mounted the transverse horizontal shaft 17, and carried by the said shaft intermediate the standards 60 is a drum or pulley 18 which is driven by means of a belt 19 driven by the engine 20 which is mounted upon a frame 21 carried by the lower beams. The said engine is preferably of the gasoline type, although any 65 desired form of engine may be used, as this forms no part of the invention.

The shaft 17 extends inwardly beyond the standard 15 and is provided with a disk 22 rigidly keyed upon the shaft, and is pro- 70 vided with a wrist-pin 23, all of which will be hereinafter more fully explained.

Extending transversely of the frame and mounted upon the upper face of the longitudinal beams 5 and 13 is a shaft 24 which is 75 mounted in journal bearings 25 carried by the beams. The said shaft carries a large drum 26 which is directly over the space between the beams 8 and 12. Between the beams 8 and 12 and 2 and 11 is an elongated vertically-arranged saw carrying member 27, 80 each side of which is provided with a pair of rollers 28 and 29, the rollers 28 of a size to snugly fit between the beams 2 and 8, and the rollers 29 between the beams 11 and 12, 85 and whereby the saw-carrying member is free to travel longitudinally and is supported by the rollers, and said rollers preventing the member from moving upwardly or downwardly.

90 The upper edge of the saw-carrying member adjacent each end is provided with eyes 30 and 31. Passing through the eye 31 is a horizontal bolt 32 carrying the nut 33, while the opposite end of the bolt is provided with 95 an eye 34. Secured to said eye 34 is a cable 35 which passes horizontally to the end of the frame and passes a pulley 36 mounted between the standards 6 and 9, and extends upward over the drum 26 and around the same. 100 The cable after making this wrap around the drum passes downwardly around the pulley 37 mounted between the standards 6 and 10, and is secured to the eye 30 carried by the opposite end of the saw-carrying member. By 105 oscillating the shaft 26 the drum is oscillated, and through the medium of the cable 35 the saw-carrying member is caused to travel back and forth. By turning the nut 33 the bolt 32 is adjusted horizontally and the cable 110

35 is tightened, and thus takes up any stretching of the cable. The saw-carrying member at the upper and lower edges have bolted or otherwise secured thereto, the 5 plates 38 and 39, and passing between said plates is the shank 40 of the saw 41, and said shank is removably clamped between these plates by the U-shaped clips 42 and 43 whereby the saw can be readily removed for 10 sharpening or for introducing a new saw therein.

The shaft 24 is provided with a drum 44. Carried by the upper face of the beams 5 and 13 are bearings 45 in which is mounted a 15 transverse horizontal shaft 46, and mounted on said shaft intermediate its ends is a lever 47 the inner end of which carries a segment 48. Wound upon said drum 44 is a cable 49 which has its ends crossed and extending 20 over the segment, and extending inwardly, and the ends of said cable extend outwardly and are connected to eyes 50 carried by the outer ends of the lever 47. Connected to the 25 extreme outer ends of the lever is a pitman 51 which has its lower end connected to the wrist pin 23.

In order to give the proper feed to the saw, as it will be seen that the saw or its connections have no vertical movement, I provide 30 means for adjusting the entire frame, whereby, as the saw cuts through the log, the frame is lower and gives to the saw the proper feed. To accomplish this result I provide the end of the frame with feet 52 on 35 which the said frame is rocked. Adjacent the said feet the frame 1 is provided with a transverse bolt 53, the ends of which extend beyond the side beams of the frame, and pivotally carried by the said projecting end 40 of the bolt on each side of the frame is a beam 54 and 55 which extend outwardly beyond the opposite end of the frame, and upon which the log to be sawed is placed. Beyond the log, or at the outer end of the beams 45 55 is an upwardly-extending frame 56 which is rigidly connected to the beams, and thus held in a vertical position. Secured to the upper end of the said frame is a pulley 57, and over said pulley a cable 58 passes, one 50 end extending to a position close to the engine, where it can be operated by the operator of the engine. The other end of the cable is secured to an eye 59 carried by the end of the frame 1, and by pulling upon the cable the frame-carrying the saw is 55 raised, and thus can be lowered to give the proper feed to the saw as it cuts its way through the logs.

In order to keep the belt 19 at the proper 60 tension I provide a pivoted frame or belt tightener 60. This belt tightener is formed of a rectangular heavy frame which is pivoted between the two upper horizontal beams of the frame 1 directly over the engine, and 65 the lower end thereof extends obliquely

downwardly and is provided with a roller or drum 61 which rests upon the belt and gives the proper tension thereto so as to operate the saw, as I will now proceed to describe.

In operation, the engine is started, the belt 70 19 rotates the shaft 17, and the disk 22, by means of the wrist-pin 14, causes the pitman 51 to move the lever 47 up and down, oscillating the segmental member 48 which, through the medium of the cable 49, oscillates the drum 44 carried by the shaft 24. The drum 26 being carried by said shaft necessarily oscillates therewith, and the cable 35 being wound upon the said drum 26, and said cable passing around the pulleys 36 80 and 37 at the end of the frame, and connected to the saw-carrying member, the same will be reciprocated back and forth to cause the saw to reciprocate, and thus properly saw the logs.

Having thus described my invention, what I claim and desire to secure by Letters Patent, is:—

1. A saw mill comprising a frame, a reciprocating saw engine and connection parts, 90 carried by the frame, feet carried by the end of the frame opposite to that of the saw, bars pivotally connected to the lower end of the frame adjacent the feet and extending parallel with the frame and beyond the end carrying 95 the saw, a frame carried by the ends of said beam, a pulley carried by the upper end of said frame, and a cable secured to the saw carrying frame and passing over the pulley whereby said frame is raised and lowered. 100

2. A saw mill, comprising a frame, a saw-carrying member horizontally reciprocating within the frame, a saw carried thereby, a drum mounted within said frame above the saw-carrying member, pulleys carried by the 105 ends of the frame, a cable wound upon the drum and having its ends passing over the pulleys and secured to the saw-carrying member, means for oscillating said drum whereby the saw is reciprocated, feet carried 110 by the opposite end of the frame from the saw, and means for rock'ing the said frame on the feet.

3. A saw mill, comprising a frame, a saw-carrying member horizontally reciprocating 115 in the frame, a saw carried by said members, a drum mounted within said frame, pulleys carried by the ends of the frame, a cable wound upon the drum and having its ends passing over the pulleys and secured to the 120 ends of the saw-carrying member, a smaller drum mounted upon the same shaft as the before mentioned drum, an arm intermediately pivotally mounted upon the shaft 125 adjacent the drums, a segmental member carried by the end of said arm, a cable having its ends secured to the arm and passing over the segmental member and crossed and wound upon the smaller drum, an engine on said frame and means connecting the end of 130

said arm and the engine whereby the same is oscillated, and a reciprocating movement imparted to the saw.

4. A saw mill, comprising a frame, a reciprocating saw carried by the frame, and projecting from one end of the frame, means carried by the frame for reciprocating the saw, a cable carried by the drum and having its ends passing over the pulleys and secured to the ends of the saw-carrying member, a smaller drum mounted upon the same shaft as the before mentioned drum, an arm intermediate pivoted upon the frame adjacent the drums, a segmental member carried by the end of said arm, a cable having its ends secured to the arm and passing over the segmental member and crossed and wound upon the smaller drum, a pitman connected to the outer end of said arm, a disk below said arm and having a wrist-pin connected to the pitman, a drum carried by the shaft-carrying disk, an engine carried by the frame adjacent the drum, a belt driven by the engine and passing over the drum, a gravity belt tightener at the end of the frame opposite the saw, bars pivotally connected to the lower end of the frame adjacent the feet and extending parallel with the frame, and beyond the end carrying the saw, a frame carried by the ends of said beam, a pulley carried by the upper end of said frame, and a cable secured to the saw-carrying frame and passing over the pulley whereby said frame is raised and lowered.

5. A saw mill, comprising a frame, a saw-carrying member horizontally reciprocating in the frame by means of horizontally pivoted rollers traveling in and between rails, a saw carried by the said member, a drum mounted within said frame, pulleys carried by the ends of the frame, a cable wound upon the drum and passing over the pulleys and attached to said saw frame, a belt for operating said drum, a belt tightener engaging said belt, feet carried by one end of the frame, a saw carrying frame pivotally attached to the frame adjacent the feet and extending along the sides and beyond the end of the frame carrying the saw, and means carried by the frame for raising and lowering the saw-carrying frame.

6. A saw mill, comprising a frame having two pairs of horizontal beams arranged side by side, an elongated horizontal saw carrying member between the pairs of beams, rollers carried by said saw carrying member between the beams of each pair, a saw carried by said member means mounted within the frame for reciprocating said saw carrying member, feet carried by the opposite side of the frame to the saw, bars pivotally connected to the lower end of the frame adjacent the feet and extending parallel with the frame and beyond

the end carrying the saw, a frame carried by the ends of said beam, a pulley carried by the upper end of said frame, and a cable secured to the saw carrying frame and passing over the pulley whereby said frame is raised and lowered.

7. A saw mill, comprising a frame, a saw-carrying member horizontally reciprocating in the frame, a saw carried by said members, a drum mounted within said frame, pulleys carried at the ends of the frame, a cable wound upon the drum and having its ends passing over the pulleys and secured to the ends of the saw-carrying member, a smaller drum mounted upon the same shaft as the before-mentioned drum, a segmental member pivotally mounted upon the frame, a cable having its ends attached to the segment and passing around the same, and crossed, and wound upon the drum, and means for rocking said segment upon its pivot whereby the saw is reciprocated.

8. A saw mill comprising a frame, a reciprocating saw mounted therein, means within the frame for reciprocating the saw, feet carried by the bottom of the frame at one end, beams pivoted to the frame adjacent the said feet, and extending beyond the opposite end, an upwardly-extending frame rigidly secured to the outer end of the frame, a pulley carried by the upper end of said frame, and a cable passing over the pulley and attached to the saw-carrying frame, whereby the same is rocked upon the feet.

9. A saw mill comprising a frame, a saw-carrying member horizontally reciprocating in the frame, a saw carried by said member, a drum mounted within said frame, pulleys carried by the ends of the frame, a cable wound upon the drum and having its ends passing over the pulleys and secured to the ends of the saw-carrying member, a smaller drum mounted on the same shaft as the before-mentioned drum, a segmental member pivotally mounted upon the frame, a cable having its ends attached to the segment and passing around the same and crossed, and wound upon the drum, means for rocking said segment, feet carried by the end of the frame opposite to that by which the saw is carried, a lifting frame pivotally attached to the frame adjacent the feet and extending beyond the opposite end, and means carried by said lifting frame for raising and lowering the frame, substantially as set forth.

In testimony whereof I affix my signature in presence of two witnesses.

DANIEL I. KEOUGH.
